UNITED STATES PATENT OFFICE.

JESSE A. HENRY, OF TORONTO, CANADA.

THILL-HOLDER.

SPECIFICATION forming part of Letters Patent No. 631,638, dated August 22, 1899.

Application filed June 26, 1899. Serial No. 721,846. (No model.)

To all whom it may concern:

Be it known that I, JESSE A. HENRY, a subject of the Queen of Great Britain, residing at Toronto, in the Province of Ontario, Dominion of Canada, have invented certain new and useful Improvements in Ball-Bearing Thill-Holders, of which the following is a specification.

The object of this invention is the production of a thill-holder arranged with a peripheral row of balls for supporting the thill, thereby providing a rolling engagement between the holder and the thill, permitting the latter to slip freely backward and forward in the holder.

In the accompanying drawings, Figure 1 is a perspective view of this thill-holder. Fig. 2 is a vertical central section of the same on dotted line $x x$ of Fig. 3, and Fig. 3 is a side view of said holder.

Like letters of reference indicate corresponding parts throughout the several views.

A is the body portion of the thill-holder, in loop form, being provided with the ball-race A' for the reception of a row of balls A². This race A' extends somewhat more than one-half the way around the body portion A at the lower side thereof, the balls projecting inward above the inner periphery of the loop.

At the lower end of the body portion A is provided the fixed loop A⁸, to which the girth of the harness is secured in the usual manner.

A⁴ is a transverse T-shaped stud integral with the body portion A of the thill-holder, extending outward from the upper portion thereof.

A⁵ is an opening formed in the upper part of the body portion A of the holder, and A⁶ is a threaded opening extending through said body portion A to one side of and a little below the opening A⁵.

The upper part of the body portion A is formed for the reception of the buckle B, which suspends the thill-holder from the saddle of the harness, the metallic strap B' holding said buckle securely in position, the rivet B² of the buckle being held in the opening B³ formed by the meeting surfaces of the body portion A and the metallic strap B'.

B⁴ is an opening formed in the upper part of the strap B', coinciding with the opening A⁵ in the upper part of the body portion A,

which coinciding openings are to accommodate the tongue of the buckle B.

B⁵ is an elongated opening through the strap B', extending lengthwise thereof, and is provided for the reception of the T-shaped stud A⁴.

B⁶ is a round-headed machine-screw provided for the threaded opening A⁶ and adapted to secure the strap B' rigidly to the upper part of the body portion A.

The ball-race A' is open at one of its ends for the reception of the balls A², being closed by the act of securing the metallic strap B' 65 in position. This strap is placed so that the stud A⁴ extends through the elongated opening B⁵ in the strap. The rivet of the buckle B is placed underneath the strap B', the tongue of said buckle extending upward through the 70 opening B³.

In practice this thill-holder is secured to the strap connecting with the saddle of the harness and the girth attached to the loop in the usual manner. The thill resting in the holder 75 is free to slide backward and forward therein, not dragging upon the holder and pulling backward or forward upon the saddle as where the ordinary leather loop is used. With the arrangement of balls as herein shown it is 80 impossible to bind or cramp the thill in the holder.

To remove the buckle B, the screw B⁶ is taken out and the metallic strap B' turned at right angles to the length of the holder and 85 slipped off from the T-shaped stud A⁴, when the buckle B may readily be separated from the said strap B'. The removal of the metallic strap B' opens the ball-race A and permits of the removal of the balls A² therefrom. 90

The girth-loop A⁸ is slightly to one side of the center line of the holder, being so placed to accommodate the latter to the curve of the saddle of the harness.

I claim as my invention—

1. In a thill-holder, in combination, a body portion in loop form, having an inner peripheral ball-race, and an opening through the wall of said thill-holder intersecting the ball-race, whereby the balls may be inserted; means 100 for closing said opening; and a series of balls for said ball-race.

2. In a thill-holder, in combination, a body portion in loop form, having an inner periph-

95

100

eral ball-race, and an opening through the wall of said thill-holder intersecting the ball-race, whereby the balls may be inserted; a strap for closing said opening; and a series 5 of balls for said ball-race.

3. In a thill-holder, in combination, a body portion in loop form, having an inner peripheral ball-race, and an opening through the wall of said thill-holder intersecting the ball- 10 race, whereby the balls may be inserted; a strap for securing a buckle to said thill- holder, having an elongated opening therein; a transverse metallic stud engaging the strap through said opening; and a series of balls 15 for said ball-race.

4. In a thill-holder, in combination, a body portion in loop form, having an inner peripheral ball-race, and an opening through the

wall of said thill-holder intersecting the ball- race, whereby the balls may be inserted; a 20 strap for securing a buckle to said thill- holder, which strap is provided with an open- ing for the reception of the tongue of the buckle, and with a longitudinally-elongated opening, also with a perforation near the op- 25 posite end of said strap; a transverse T-shaped stud formed integral with the body portion of the thill-holder, adapted to engage said elongated opening; a screw for the perfora- 30 tion near the opposite end of said strap; and a series of balls for said ball-race.

JESSE A. HENRY.
